Primary Examiner — Darlington Ly(74) *Attorney, Agent, or Firm* — Muncey, Geissler, Olds & Lowe, P.C.(57) **CLAIM**

The ornamental design for an electric tricycle, as shown and described.

DESCRIPTION

FIG. 1 is a top, front, and right side perspective view of an electric tricycle showing our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines in the drawings illustrate portions of the electric tricycle that form no part of the claimed design.
